UNITED STATES PATENT OFFICE.

CHARLES A. COLOMB, OF ELGIN, ILLINOIS.

GAME APPARATUS.

970,993.

Specification of Letters Patent. Patented Sept. 20, 1910.

Application filed December 22, 1909. Serial No. 534,483.

To all whom it may concern:

Be it known that I, CHARLES A. COLOMB, a citizen of the United States, residing at Elgin, in the county of Kane, State of Illinois, have invented certain new and useful Improvements in Game Apparatus; and I do hereby declare the following to be a full, clear, and exact description of the invention, such as will enable others skilled in the art to which it appertains to make and use the same.

This invention relates to improvements in game apparatus, of the class comprising a board having a plurality of right angled 15 crossing lines and diagonal lines, and a plurality of "men" or figures to be moved upon the lines, and has for one of its objects to produce a device of this character calculated to instruct and amuse a player and to exercise the mind during the playing.

With this and other objects in view, the invention consists in the arrangement and construction of the board and the "men" or figures, as hereinafter shown and described 25 and then specifically pointed out in the claim; and, in the drawing.

The figure represents a plan view of the improved device with the "men" or figures thereon as they will appear at the starting 30 point of the game.

The board may be of any required size and of any suitable material, and is represented as a whole at 10, and is preferably square and provided with a projecting portion 11 also preferably square but of smaller area than the main board 10. The board 10—11 is provided with a plurality of right angled lines 12 crossing each other and producing a plurality of square surfaces in 40 checker-board form, the right angled lines produced into the projecting portion 11 and extending the square figures into this extended portion.

The lines 12 upon the main body 10 form 45 a series of square figures of equal sizes, and extending diagonally across the lines 12 of the body 10 are two diagonal lines 13—14, the diagonal lines being arranged to "cut" across the corners of the squares over which 50 they pass, as shown.

Extending diagonally across the squares of the extension 11 are two diagonal lines 55 15—16, these latter diagonal lines also cutting across the corners of the square figures upon the extension 11. Any required number of the "men" may be employed, and one

special man or figure will also be employed and designated in any distinctive manner.

For the purpose of illustration a board having thirty-six square figures upon the body portion and four square figures upon the extension is shown, but it will be understood that any required number of the square figures may be employed and arranged in any desired order, but the figures 65 will preferably be arranged as shown.

For the purpose of illustration fourteen of the playing figures or "men" are shown and represented at 17 and one special figure represented at 18. Any distinctive marks may 70 be employed upon the figures 17 and 18 to designate them, but for the purpose of illustration some of the figures 17 are marked "Hunter" and some marked "Dog", while the figure 18 is marked "Lion", the game being preferably designed to represent a lion hunt.

In starting the game the figures 17 are arranged upon the crossing points of the lower two rows of figures, while the "lion" 80 figure is arranged upon any of the other crossing points upon the board not occupied by the figures 17, for instance upon the crossing points next above the upper line of the figures 17. Any number of persons may 85 play the game, but one player will be designated to operate the figure 18, while the remaining players operate the figures 17 in order. It will be understood that the figure 18 and one of the figures 17 must be moved 90 alternately, that is to say every time that one of the figures 17 is moved the figure 18 must be next moved, and so on continuously, and the game is for the player or players 95 who are designated to operate the figures 17 to drive the lion 18 into the extension 11, while the object of the player who is designated to operate the lion figure is to "jump" the remaining figures and remove them from the board, and if the player who is operating 100 the lion figure succeeds in capturing a certain predetermined number of the "men" 17, he wins the game, but if the players who are operating the figures 17 succeed in driving the lion into the extension 11 they win 105 the game. The figures 17 being prohibited from "jumping" the figure 18, while the figure 18 is permitted to "jump" the figures 17, gives the single figure 18 an equal advantage with the numerous figures 17, and 110 by manipulating the figures 17 the figure 18 may be surrounded or forced to move to-

ward the extension 11, and this moving of the figure 18 is called "driving," and the efforts of the persons moving the figures 17 will be to thus drive the figure 18 into the extension 11, as above noted. The figures must all move upon the lines upon the board either diagonally upon the lines 13—14 or 15—16 or upon the square lines 12, and may be moved in any direction. The figures 17 are not permitted to "jump" the figure 18, but the figure 18 can "jump" any of the figures 17, provided, in the course of the movement, one of the figures 17 is located upon a pair of the crossing lines next to the lion figure and with a vacant set of crossing lines at the opposite side of the figure 17, similar to the "jumping" operations of the "king" in the game of checkers.

It will be obvious that many different rules may be devised for controlling the playing of the game, and it is not thought necessary to elaborate more fully in the description of the playing of the game, but to illustrate the action, in starting the game one of the "men" 17 is moved along one of the lines 12 or the lines 14—16, but they must be careful not to expose the figure which is moved to the danger of being jumped by the lion figure 18. The lion figure is then moved in any desired direction, the aim being to locate the figure 18 in the rear of one of the hunter figures, and the skill of the players who operate the figures 17 is exercised to avoid being jumped by the lion figure and also to drive the lion figure into the extension 11, while the skill of the player who operates the lion figure is exer-

cised to move the lion figure into position to enable it to jump the "hunter and dog" figures and to avoid being driven into the extension 11.

It will thus be obvious that a simply devised and interesting game apparatus is produced which requires thought and skill to "play," and will exercise the thinking and calculating faculties in the same manner as playing the game of draughts or checkers.

The board may be colored in any desired manner, and the figures of the "men" may be of any suitable material and of any suitable form.

What is claimed is:

A game apparatus comprising a board formed of a body portion and an extension portion, said body and extension portions being each provided with a plurality of lines crossing at right angles, diagonal lines crossing the body of the board obliquely and cutting the right angled lines at their crossing points, diagonal lines crossing the extension portion of the board obliquely and cutting the right angled lines thereon at their crossing points, a special figure having a distinctive designation, and a plurality of figures having distinctive designations, said figures being movable upon said right angled and oblique lines.

In testimony whereof, I affix my signature, in presence of two witnesses.

CHARLES A. COLOMB.
